(57) **CLAIM**

The ornamental design for a foldable bag, as shown and described.

DESCRIPTION

FIG. 1 is a front perspective view of a foldable bag showing my new design;

FIG. 2 is a top perspective view thereof;

FIG. 3 is a side perspective view thereof;

FIG. 4 is a second front perspective view thereof;

FIG. 5 is a front plan view thereof;

FIG. 6 is a third front perspective view thereof;

FIG. 7 is an end perspective view thereof;

FIG. 8 is a an end plan view thereof;

FIG. 9 is a bottom plan view thereof; and,

FIG. 10 is a top plan view thereof.

The broken lines shown in the drawings are included for the purpose of illustrating environmental structure and form no part of the claimed design.
